UNITED STATES PATENT OFFICE.

MALCOLM S. JOHNSON, OF CHICAGO, ILLINOIS, ASSIGNOR TO E. PAYSON SMITH, OF SPRINGFIELD, ILLINOIS.

BRAKE-HANGER SUPPORT.

Application filed January 10, 1927. Serial No. 160,122.

My invention relates to means for supporting the hangers which pendently hold the brake beams in place from the truck side frame. Truck side frames as at present more generally employed comprise a one piece structure of cast or pressed steel. With my invention, the side frames on the inner sides thereof, adjacent to the vertical members of the side frame, are provided 5 with laterally disposed arms of predetermined length having flanges arranged in vertically spaced relation and preferably connected adjacent the ends to provide a socket or pocket therebetween adapted to receive a pin supporting and thrust receiving means adapted to be removably secured in the socket or pocket in a manner which will permit its ready removal and the replacement of parts when desired in order that 10 the support may be adapted to the U-shape link type of hanger as well as to the continuous link type of hanger.

The invention also involves a construction 25 wherein the hanger supporting pin, where the U-shape type of hanger is employed, may be reversed relative to its ends so that any wear on the supporting pin may be transferred to other portions thereof and the life of the supporting means thus enhanced; while at the same time providing 30 a structure wherein loss of parts when properly assembled is impossible.

The above enumerated objects and advantages, as well as others inherent in the invention, will be more readily comprehended 35 from the detailed description of the accompanying drawings, wherein—

Figure 1 is a side elevation of one end or portion of a truck side frame, showing in 40 dotted lines the position of my improved hanger supporting means.

Figure 2 is a vertical sectional elevation as viewed substantially on the line 2—2 of Figure 1 looking in the direction of the 45 arrows.

Figure 3 is a vertical sectional view taken substantially on the line 3—3 of Figure 2 looking in the direction of the arrows.

Figure 4 is a cross sectional view taken 50 on the line 4—4 of Figure 2 looking downwardly.

Figure 5 is a side elevation of the supporting means and integral portions of the side frame with parts of the latter shown in 55 section and portions of the hanger broken

away; the view illustrating a modification adapted to the application of the continuous link type of hanger.

Figure 6 is a vertical sectional view taken on the line 6—6 of Figure 5 looking in the 60 direction of the arrows.

Figure 7 is a cross sectional view taken on the line 7—7 of Figure 5 looking downwardly.

Figure 8 is a longitudinal sectional view 65 substantially similar to Figure 7 illustrating the use of the U-shape type of hanger as employed in Figure 2.

Figure 9 is a detail perspective view, looking upwardly, of the retainer element employed with the construction shown in Figure 5.

The invention has for its object the provision of means whereby the supporting links, whether of the U-shape or continuous 75 link type may not only be securely held in place and all wear taken up by the keeper or retainer element, but the assembly and positioning of the various elements readily made and obtained, while at the same time permitting 80 a substitution of the one type of supporting hanger for the other without necessitating alteration in the portions integral with the truck side frame.

In Figures 2 to 4, I illustrate my improved 85 means used in connection with the U-shape type of hanger or link, a portion of the side frame being shown at 15. The inner side of the side frame, namely the side disposed toward the wheels of the truck and adjacent 90 to the vertical portions or compression members of the side frame is provided with an integral transversely disposed arm or projecting portion 16 having at its top the flange portion 17; the outer end whereof is 95 shown provided with an integral vertically disposed flange portion 18 extending downwardly and preferably connecting with the laterally disposed flange portion 19. The flange portion 19 is shown provided with a 100 reinforcing rib 20 formed integral with the arm 16 secured to the side frame. In alignment with the flange portion 19, I provide a laterally disposed flange portion 21, 105 which likewise is preferably provided with the reinforcing ribs 22; and in spaced relation and in horizontal alignment with the flange portion 21; I provide the flange portion 23 made preferably with the angular or off-set end flange portion 24 110

which also connects with the upper flange portion 17 at a point slightly removed from the side frame proper. The end flange portion 24 is offset or of the irregular angular construction shown in Figure 2 to provide a pocket or socket as at 25 and with end flange 18 provides a closure for the hanger supporting pin. The various flange portions 19, 21 and 23 are not only in predetermined horizontal spaced relation, but are arranged in vertical spaced relation with the top flange portion 17 and are all of sufficient transverse dimensions to provide a suitable pocket or enclosure adapted to receive a block like 15 retainer or keeper and wear-receiving element 26 which is preferably of the rectangular formation more clearly disclosed in Figure 4. The flange portions 19, 21 and 23 are spaced apart a sufficient distance to provide 20 slots through which the hanger 27 depends. The hanger 27, as employed in Figures 2 to 4, is of the U-shape type with the upper ends enlarged or eyeleted as shown at 28 in Figure 3 to receive the supporting pin 29, which latter preferably extends substantially from end wall or flange 18 to the offset end wall or flange portion 24, see Figures 2 and 4, in order that longitudinal movement of the pin will not take place.

30 The keeper element or retainer 26 is in the nature of a rectangular block which, for the sake of lightness is cut away or cored, as shown at 30 and 31. The depth of the pocket between flange portions 17, 19, 21 35 and 23 and the transverse dimensions of the keeper element are such that the forward face of the keeper element will extend substantially flush with the forward edges of the flange portions. The top and bottom flange portions 17 and 21, as well as the keeper element 26, are shown provided with ears or extensions 17^a, 21^a and 26^a, respectively, which are apertured to receive the keeper retaining bolt 32, held in place by nut 45 32^a, while the bolt is held against rotation by having its head in abutting relation with an upstanding lug 33 formed on the top flange 17, see Figure 3.

The keeper element is preferably formed 50 so as to contact at its ends with the end flanges or walls 18 and 24, by reason of the boss formations 34, 34, see Figures 2 and 4. The keeper block 26 is provided with an opening extending longitudinally therethrough as well as through the boss formation 34, 34, to receive the supporting pin 29; the boss formations or enlargements 34 thus 55 also providing a greater bearing surface for the ends of the pin 29.

60 The keeper block 26 is provided with transversely extending sockets 35, 35, open at bottom and at the front face of the block in order to receive the enlarged eyeleted ends 28 of the hanger or link 27 and permit free oscillatory movement of the latter; the link 65

depending through the open bottom of the sockets 35, 35.

In practice, the upper ends of the link 27 are inserted into the keeper block 26 and the supporting pin 29 then inserted endwise 70 through the hole in the block and through the eyes of the link; the block or keeper element 26 is then inserted into the pocket formed between the spaced parallel flange portions, after which the locking bolt 32 is 75 inserted in place. It is apparent from this construction that the upward and downward thrusts of the hanger or link 27 are entirely transmitted to the keeper block through the pin 29 and therefore any wear encountered 80 will be on parts which may be readily removed and replaced, namely the pin 29 and the keeper block 26 and no wear on parts formed integral with the truck side frame can take place. This is quite an important 85 feature and eliminates the excessive cost of side frame repair and replacement.

In Figures 5 to 9, I illustrate a modified form of my invention, wherein the supporting means is adapted to both the U-shaped 90 type and to the continuous link type of hanger.

The truck side frame 15, like that in the previously described figures, is provided with an integral arm or projection 16, having the top and bottom flange portions 17, 19, 21 and 23; with the top flange portion 17 being connected at its end with the bottom flange portion 19 by means of the vertical end flange portion 18 and said top flange 95 portion also having the end forming flange portion 23 connected therewith; the flange portion 23 having the intermediate offset 24 to provide a socket for one end of the supporting pin 29 when the U-shape type of 100 hanger is employed.

The arm or projection 16 in the construction shown in Figures 5 to 8, at an intermediate point, has its vertical wall provided with a forwardly presented lug 36 formed 110 integral therewith and disposed at a point intermediate of the top flange portion 17 and the bottom flange portion 21, see Figure 6. The forward end of the lug 36 is undercut or formed arcuate as shown at 37 to 115 leave an overhanging lip 37^a, in order to conform with the curvature of the upper end of the link hanger 38 or of the supporting pin 29 when the latter is employed; Figures 5, 6 and 7 illustrating the use of the 120 continuous link type of hanger. The retainer or keeper element 39, employed with this construction, is likewise of the more or less rectangular block form shown in Figure 9, being cored or cut away adjacent to 125 the ends and from the bottom thereof as shown at 40 in Figure 9 to provide a passage for the insertion of the upper end of the link or hanger; the cored or cut-away portion also extending longitudinally of the 130

keeper element adjacent to the rear or inner wall 41 of said element and thus leaving the intermediate elongated lug 42 at the forward or outer side of the keeper element. The 5 intermediate boss or lug 42 is cored out or cut away to leave the end portions or transversely extending ribs 43 shown in dotted lines in Figure 6 above the passage 40 adjacent the rear wall of the lug 42; and the 10 lug 42 is cored longitudinally to provide a pin or link-receiving socket 44 which communicates above the bottom of the socket with the rear part of passage 40, thus leaving the upstanding lip 44^a. The end walls 15 of the retainer element or keeper are apertured at 45 in alignment with the socket 44 in order that a supporting pin, like that shown at 29 in Figure 8, may be disposed through the end walls of the keeper element 39 with one end of the pin entering the socket 24 formed in one end of the 20 pocket in arm 16. The rear wall 41 of the retainer or keeper element 39 is provided with an opening 46 for passage of the boss 25 or lug 36 therethrough; the opening 46 communicating with the slot or passage 40. The forward end of the boss or lug 36 is adapted to abut against the intermediate lug 42 of the keeper element; its undercut forward 30 side, in conjunction with the socket portion 44 on the rear side of the intermediate lug 42, constituting complementary socket-forming elements to receive the upper end of the supporting link 38 or the supporting 35 pin 29 when the U-shape type of hanger 27 is employed. The boss or lug 36 extends intermediate of the ribs 43 of the keeper element 39.

The keeper element 39 is also shown provided with a vertically disposed aperture 47 extending through the forward side thereof adapted to register with apertured extensions 17^a and 21^a of the pocket forming flange on the arm 16, to receive a suitable 45 bolt 32 whereby the keeper element is secured in place.

As the retainer or keeper element 39, with its end wall bosses or enlargements 39^a, 39^b substantially fills the pocket formed on the 50 arm 16 by the various flange portions and as the boss or lug 36 fits between the ribs 43, 43, it is apparent that the keeper element will be held in position against longitudinal movement, while the bolt 32 will lock the 55 same in place.

In practice, the upper end of the link hanger 38 is inserted through the passage 40 rearward of the intermediate lug 42 of the keeper element and placed in the passage 44 forward of the lip 44^a, after which the keeper element 39 with the suspended link is then inserted into the pocket formed in the arm 16; the sides of the link 38 depending through the vertically disposed portions 60 of the passage 40 adjacent to opposite ends

of the keeper element and between the lower flange portions 19 and 21 and between 21 and 23, thus allowing the link to have the necessary oscillatory movement. The link is held in the undercut socket 44 at the rear 70 side of the keeper element by the boss or lug 36 formed integral with or secured to the arm 16, as is apparent from Figure 6. It is evident that wear, due to the down thrusts encountered by the link, will be taken up 75 by the keeper element which may be readily replaced if the wear becomes too pronounced, by simply removing bolt 32 which will permit the keeper element with the link to be withdrawn from the pocket in the arm 16. 80

Where it is desired to employ the U-shape type of hanger 27, the eyeletted upper ends of the link are passed into the cored portions or passage 40 on opposite sides of the intermediate lug 42, the supporting pin 29 then inserted endwise through the openings 45 in the ends of the keeper element, and through the eyeletted ends of the hanger 27; the pin having bearing at its ends in the enlarged end walls of the keeper element, 90 in the undercut groove 44 at the rear of the intermediate lug 42 of the keeper element while one end of the pin will be seated in the off-set end wall of the pocket. The keeper element with the suspended hanger 95 is then inserted into the pocket formed in the arm 16 in the manner previously described in connection with the continuous link type.

With the pocket forming flange portion 23 having the offset formation shown in Figures 2 and 5, it is apparent that a longer supporting pin 29 may be employed than would be the case if the flange portion 23 were vertically disposed throughout its entire length like the opposite end flange portion 18. The purpose in forming the end flange portion 23 as shown and described is to permit the use of a longer pin, in order that the worn portions of the pin, induced by the eyeletted ends of the hanger 27, may be shifted by removing the pin and reversing it end for end, which will cause different portions of the pin 29 to register with the eyeletted ends of the hanger 27 on opposite sides of keeper lug 42, thereby greatly enhancing the life of the construction. 115

The constructions illustrated have been described in terms which are employed merely as terms of description and not as terms of limitation, as structural modifications may 120 be made without, however, departing from the spirit of my invention.

What I claim is:—

1. A brake hanger support comprising, in combination with a truck side-frame having an inwardly projecting arm formed to provide a horizontally disposed pocket open on one side and having a pair of spaced slots in the bottom, a keeper element consisting of a rectangular block seatable in said pocket, 130

and having vertically disposed slots adjacent to opposite ends of the block, open at bottom and the outer face of the block, said block being provided with a longitudinal channel 5 extending entirely therethrough and intersecting said slots.

2. A brake hanger support comprising, in combination with a truck side-frame having an inwardly projecting arm provided with laterally extending flanges on one face forming a rectangular pocket, the lower flange being cut away adjacent to the side wall forming flanges of the pocket, a keeper element consisting of a rectangular block seatable in said pocket, said block being cored to provide a channel extending lengthwise therethrough and having slots extending upwardly from the bottom and intersecting said channel.

3. In a brake hanger support, the combination of a truck side-frame having an arm extending inwardly therefrom adjacent to the vertical compression members thereof, said arm having a vertical face of comparative width provided with a laterally disposed continuous flange arranged to provide an elongated pocket disposed lengthwise of the arm, and a keeper element seatable in said pocket, said element consisting of an elongated block 30 channeled lengthwise and slotted vertically from its bottom adjacent opposite ends with the slots intersecting the channel, and means for removably holding the keeper element in place.

4. A brake hanger support comprising the combination of a truck side-frame provided with a laterally disposed arm having a vertical face with a horizontally extending flange defining a rectangular shaped pocket, a rectangular block slideable into said pocket and cored to provide a channel extending lengthwise of the block and a pair of channels adjacent to the ends of the block, open at front and bottom of the block and intersecting the first mentioned channel.

5. In a brake hanger support, the combination of a truck side-frame provided on its inner side with a pocket open toward the wheels of the truck, the upper and lower walls of the pocket having registering bolt receiving holes, with a retainer element for the brake hanger, seatable in said pocket and comprising an elongated block cored to provide a channel extending therethrough, and

a pair of transverse channels adjacent to the ends extending upwardly from the bottom of the block and intersecting the first mentioned channel, the portion of the block intermediate of said transverse channels being provided with a bolt receiving hole adapted to register with the holes in the walls of the pocket.

6. In a brake hanger support, the combination of a truck side-frame provided on its inner side with a pocket open toward the

wheels of the truck, with a retainer element for the brake hanger, seatable in said pocket and consisting of an elongated block cored to provide a channel adjacent to each end of the block extending upwardly from the bottom side of the block and a channel extending lengthwise and intersecting the first mentioned channels, a portion of the last mentioned channel intermediate of the points of intersection with the other channels being

70

open toward the rear side of the block and accessible from the bottom of the block.

75

7. In a brake hanger support, the combination of a truck side-frame provided with a pocket opening toward the wheels of the truck, with a retainer element for the brake hanger, seatable in said pocket and comprising a block cored to provide a longitudinal channel therethrough and having a pair of transverse channels extending upwardly from the bottom adjacent to the ends of the block and intersecting said longitudinal channel, said block being also provided with a fourth channel extending upwardly from the bottom of the block adjacent to one side thereof, said last mentioned channel connecting with the inner ends of said pair of channels and with the portion of the longitudinal channel intermediate of the pair of channels.

95

8. In a brake hanger support, a keeper element comprising an elongated block having a pin receiving opening longitudinally therethrough, and slotted upwardly from the bottom of the block, the ends of the slot extending toward and opening at the front face of the block and intersecting the longitudinal opening, while the intermediate portion of said slot communicates with one side of the longitudinal opening intermediate of said points of intersection.

100

9. In a brake hanger support, a keeper element comprising a rectangular block having a pin receiving passage extending lengthwise therethrough and a slot extending upwardly from the bottom, the ends of the slot being disposed parallel with the block ends in intersecting relation with said pin receiving passage and opening through the forward face of the block, while the intermediate portion of the slot communicates with the side of said passage adjacent to the rear face of the block and above the bottom of said passage.

110

10. In a brake hanger support, the combination of a truck side-frame provided with an inwardly extending arm, a side whereof is provided with a pocket open toward the wheels of the truck, a keeper element slideable laterally into said pocket and comprising a block having a pin receiving passage extending lengthwise therethrough and a slot extending upwardly from the bottom with the ends intersecting the passage and disposed through the forward face of the block,

115

120

125

130

and means disposed through the wall of the pocket whereby the block is held in place.

11. In a brake hanger support, the combination of a truck side-frame provided with an inwardly extending arm, a side wall whereof is provided with a pocket open toward the wheels of the truck, a keeper element slideable laterally into said pocket and comprising a block having a pin receiving passage longitudinally therethrough, a wall of the pocket at one end of the block being off-set at a point in alignment with the pin passage to provide a pin-end receiving socket, said block having a slot extending upwardly from the bottom, the ends of the slot intersecting said passage and disposed through the forward side of the block, and means whereby the block is locked in place.
12. In a brake hanger support, the combination of a truck side frame provided with a socket opening toward the wheels of the truck, with a keeper block seatable in said socket and having a longitudinal channel to receive a brake hanger, the rear wall of the block having an opening which connects with the channel in said keeper block, and an integral portion on the truck frame adapted to extend into said opening in the

rear wall of the block and having its forward face made to conform with the brake 30 hanger.

13. In a brake hanger support, the combination of a truck side frame provided with a socket opening toward the wheels of the truck, the upper and lower walls of said 35 socket being provided with registering apertures, with a keeper element seatable in said socket and having a longitudinal channel to receive a brake hanger, means whereby movement of the keeper element lengthwise 40 of said socket is prevented, and means whereby the keeper element is locked in place.

14. In brake hanger supporting means, an arm secured at one end to the frame of a 45 car truck while the outer end is provided with two vertically spaced portions extending laterally from one side of the arm, the outer ends of said portions having aligned apertures, the opposite sides of said portions adjacent to their inner ends being connected by vertical webs disposed forward of the rear vertical wall of the arm to provide a three sided pocket at the inner ends of said portions.

MALCOLM S. JOHNSON.
